UNITED STATES PATENT OFFICE

166,291

RADIO CABINET

Samuel E. Adler, Chicago, Ill.

Application December 29, 1951, Serial No. 17,872

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Radio Cabinet, of which the following is a specification, reference being had to the accompanying drawings, forming part thereof.

Fig. 1 is a front elevational view of a radio cabinet, showing my new design;

Fig. 2 is a top plan view thereof;

Fig. 3 is an elevational view of the right side of the cabinet; and

Fig. 4 is a sectional view the origin of which is indicated by line 4—4 of Fig. 1.

The left side of the cabinet resembles the right side and the back is plain.

The dotted lines shown in Fig. 4 are for illustrative purposes only.

I claim:

The ornamental design for a radio cabinet, as shown and described.

SAMUEL E. ADLER.
